US0D1041661S

(12) **United States Design Patent** (10) Patent No.: **US D1,041,661 S**
(45) Date of Patent: ** Sep. 10, 2024

(54) **PORTABLE ELECTROCARDIOGRAM
DEVICE WITH TOUCHSCREEN DISPLAY**

(71) Applicant: **INMEDIX, INC.**, Normandy Park, WA (US)

(72) Inventors: **Andrew James Holman**, Seattle, WA (US); **Steven Ross Daly**, Sammamish, WA (US); **Michael Glenn Loveless**, Etobicoke (CA); **Rade Gadzic**, Etobicoke (CA); **Sunghyun Lee**, Toronto (CA)

(73) Assignee: **INMEDIX, INC.**, Normandy Park, WA (US)

(**) Term: **15 Years**

(21) Appl. No.: **29/857,903**

(22) Filed: **Oct. 26, 2022**

(51) LOC (14) Cl. **24-02**

(52) U.S. Cl.

USPC **D24/167**

(58) **Field of Classification Search**

CLAIM

The ornamental design for a portable electrocardiogram device with touchscreen display, as shown and described herein.

DESCRIPTION

FIG. 1 is a top perspective view of a portable electrocardiogram device with touchscreen display;
 FIG. 2 is a bottom perspective view of the portable electrocardiogram device with touchscreen display of FIG. 1;

FIG. 3 is a front view of the portable electrocardiogram device with touchscreen display of FIG. 1.

FIG. 4 is a rear view of the portable electrocardiogram device with touchscreen display of FIG. 1.

FIG. 5 is a left side view of the portable electrocardiogram device with touchscreen display of FIG. 1.

FIG. 6 is a right side view of the portable electrocardiogram device with touchscreen display of FIG. 1.

FIG. 7 is a top view of the portable electrocardiogram device with touchscreen display of FIG. 1.

FIG. 8 is a bottom view of the portable electrocardiogram device with touchscreen display of FIG. 1.

FIG. 9 is a top perspective view of the portable electrocardiogram device with touchscreen display of FIG. 1 with the lid opened.

FIG. 10 is a bottom perspective view of the portable electrocardiogram device with touchscreen display of FIG. 1 with the lid opened.

FIG. 11 is a front view of the portable electrocardiogram device with touchscreen display of FIG. 1 with the lid opened.

FIG. 12 is a rear view of the portable electrocardiogram device with touchscreen display of FIG. 1 with the lid opened.

FIG. 13 is a left side view of the portable electrocardiogram device with touchscreen display of FIG. 1 with the lid opened.

FIG. 14 is a right side view of the portable electrocardiogram device with touchscreen display of FIG. 1 with the lid opened.

FIG. 15 is a top view of the portable electrocardiogram device with touchscreen display of FIG. 1 with the lid opened.

FIG. 16 is a bottom view of the portable electrocardiogram device with touchscreen display of FIG. 1 with the lid opened.

FIG. 17 is a top perspective view of the portable electrocardiogram device with touchscreen display of FIG. 1 with the handle extended.

FIG. 18 is a bottom perspective view of the portable electrocardiogram device with touchscreen display of FIG. 1 with the handle extended.

FIG. 19 is a front view of the portable electrocardiogram device with touchscreen display of FIG. 1 with the handle extended.

FIG. 20 is a rear view of the portable electrocardiogram device with touchscreen display of FIG. 1 with the handle extended.

FIG. 21 is a left side view of the portable electrocardiogram device with touchscreen display of FIG. 1 with the handle extended.

FIG. 22 is a right side view of the portable electrocardiogram device with touchscreen display of FIG. 1 with the handle extended.

FIG. 23 is a top view of the portable electrocardiogram device with touchscreen display of FIG. 1 with the handle extended.

FIG. 24 is a bottom view of the portable electrocardiogram device with touchscreen display of FIG. 1 with the handle extended.

FIG. 25 is a top perspective view of the portable electrocardiogram device with touchscreen display of FIG. 1 with the lid opened and tilted.

FIG. 26 is a bottom perspective view of the portable electrocardiogram device with touchscreen display of FIG. 1 with the lid opened and tilted.

FIG. 27 is a front view of the portable electrocardiogram device with touchscreen display of FIG. 1 with the lid opened and tilted.

FIG. 28 is a rear view of the portable electrocardiogram device with touchscreen display of FIG. 1 with the lid opened and tilted.

FIG. 29 is a left side view of the portable electrocardiogram device with touchscreen display of FIG. 1 with the lid opened and tilted.

FIG. 30 is a right side view of the portable electrocardiogram device with touchscreen display of FIG. 1 with the lid opened and tilted.

FIG. 31 is a top view of the portable electrocardiogram device with touchscreen display of FIG. 1 with the lid opened and tilted; and,

FIG. 32 is a bottom view of the portable electrocardiogram device with touchscreen display of FIG. 1 with the lid opened and tilted.

The broken lines shown are for the purpose of illustrating portions of the portable electrocardiogram device with touchscreen display that form no part of the claimed design.
